Patented Oct 14, 1856

Des. 845

Hudson E. Bridge of St Louis, Mo.
Letters Patent No. 845, Dated Dec. 14th 1856.

The schedule referred to in these Letters Patent, and making part of the same.

To all whom it may concern:

Be it known that I, Hudson E. Bridge, of the City and County of St. Louis, and State of Missouri, have invented or produced, a new ornamental design for the top, base, and clover, of a street - iron, airtight stove; and I do hereby declare that the following is a full and exact description thereof, reference being had to the accompanying drawings, making part of this specification. -

Fig. 1, being a plan of the top; Fig. 2, a plan of the base; and Fig. 3, a front elevation of the clover.

The top, or cornice (Fig. 1.) has a simple moulding A, on its inner margin; and immediately outside of said moulding, a plain band B, on which the name, number, state of patent, &c, are formed in relief. Outside of this band, is the ornamental border, composed of foliations a, a, at the ends, sides, and equidistant between the same. From the sides of the end and side foliations, spread partly, unrolled leaves b, b, and at the sides of the intermediate foliations, are full-blown blossoms. A plain margin D, surrounds the whole.

The base (Fig. 2) has the inner moulding A, band B, and plain margin D, similar to the corresponding parts of the top. The outline of the ornamental border is scroll-affected in the manner represented. Each lobe of the border, except the back one, is ornamented with a plant, rising from a little arch'd; the large front ornament g, surrounding a cresting e, and the four corner plants i, i, i, i, surrounding similar crestings g, g, g, g.

Should ornaments h, h, and low back ones m, do not share the extinctions. Beyond the plants, a vine m, extends the inner margin, showing leaves t, t, and berries k, k, in the open spaces t, t, and clusters of grapes s, s, growing thereon.

What I claim, and desire to secure by Letters Patent, is the configuration, comprising an ornamental design, for the top, base, and door, of a sheet-iron, air-tight stove, substantially as represented and described.

The above specification of a new and original design for the castings for a sheet-iron air-tight stove, signed by the inventor this twenty ninth day of August 1856.
